UNITED STATES PATENT OFFICE.

JAMES P. ORR, OF PITTSBURG, PENNSYLVANIA.

CROSSING FOR CABLE RAILWAYS.

SPECIFICATION forming part of Letters Patent No. 439,547, dated October 28, 1890.

Application filed December 18, 1889. Serial No. 334,180. (No model.)

To all whom it may concern:

Be it known that I, JAMES P. ORR, of Pittsburgh, in the county of Allegheny and State of Pennsylvania, have invented a new and Improved Crossing for Cable Railways, of which the following is a full, clear, and exact description.

The object of the invention is to provide a new and improved crossing specially designed for cable railways, and so arranged as to bring the crossing cables near each other, at the same time preventing the cables from coming in contact.

The invention consists of a frame carrying two sets of pulleys, of which one supports the main cable, while the crossing cable passes underneath the other set of pulleys.

The invention also consists of certain parts and details and combinations of the same, as will be hereinafter fully described, and then pointed out in the claims.

Reference is to be had to the accompanying drawings, forming a part of this specification, in which similar letters of reference indicate corresponding parts in all the figures.

Figure 1 is a plan view of the improvement. Fig. 2 is a sectional side elevation of the same on the line $x-x$ of Fig. 1, and Fig. 3 is a detail sectional view on the line $y-y$ in Fig. 1. Fig. 4 is a plan view of the crossing. Fig. 5 is a sectional side elevation of the grip.

As illustrated in Figs. 1 and 4, the main track A is crossed at right angles by the track B, and the said main track is provided with the usual rails A' and A², while the other track B is provided with the two rails B' and B². The rails A' and A² are provided with the sections A³ and A⁴ between the rails B' and B², and in a similar manner sections B³ and B⁴ are placed in the rails B' and B² between the rails A' and A². The several sections A³ A⁴ and B³ B⁴ form the middle openings A⁵ and A⁶, B⁵ and B⁶ for the passage of the cable-grips held on the cars passing over the said tracks A and B, respectively.

The openings B⁵ and B⁶ are in line and form part of the grip-slot A⁷ of the main track A, while the other openings A⁵ and A⁶ are in line and form part of that part B⁸ of the grip-slot A⁷ which bends to one side at the crossing of the tracks A and B, as plainly illustrated in Fig. 4, which bent and slot part

serves to swing the cable-grip of the track B to one side, as hereinafter more fully described.

55

In the track A is located the cable C, and the track B is provided with the cable D, the former passing over the pulleys E and E' and the cable D passing under the pulleys F and F', arranged at right angles to the pulleys E and E', respectively. The four pulleys E, E', F, and F' are mounted to turn in a light frame G, supported by cable D and held in position by a lever H, extending in the direction of the cable D. When the frame G 65 is in the position shown in Fig. 2, the car, with its grip passing over the main track A, is propelled by the cable C, which is lifted off the pulleys E and E' when the car passes the crossing, and the frame G is held in position 70 by lever H when cable C is lifted off pulleys E E'.

When the side-track car, with its grip D', passes onto the crossing on the track B, then the cable D is released from the grip-jaws 75 and the grip swings to one side in passing through the bent part B⁸ of the slot B⁷.

At the intersections of the two track-rails A' and A² with the crossing-track rails B' and B² are arranged short rails I I' I² I³, respectively, which stand in line with the main-track rails A' and A² when a car passes over the main track A on the crossing; but when a car is to pass over the track B then the position of the said rail-sections I, I', I², and I³ is 80 changed, so as to make the rails B' and B² continuous to prevent any jar of the car when passing over the crossing.

The device for changing the position of the short rail-sections I, I', I², and I³ is as follows: 90 The said sections are secured on disks I⁴, each fastened at the upper end of a vertical shaft J J' J² J³, respectively mounted to turn in suitable bearings in the car-track. On the shaft J is secured a crank-arm K, pivotally connected 95 by a link K² with a crank-arm K' on the shaft J², which latter is located opposite the shaft J in line with the rail A'. The shaft J' is provided with a crank-arm K³, pivotally connected by a link K⁵ with a crank-arm K⁴, secured on the shaft J³. A crank-arm K⁶, standing in an opposite direction to the arm K', is secured on the shaft J², and is pivotally connected by a link K⁸ with a crank-arm L', se-

cured on a longitudinally-extending shaft L, mounted to turn in suitable bearings in the track B and parallel with the rails thereof. On the shaft J³ is secured a crank-arm K⁷, 5 extending in an opposite direction from the crank-arm K⁴, and pivotally connected by a link K⁹ with a crank-arm L² on the shaft L, previously mentioned. When the shaft L is turned, the crank-arms L' and L² by their connections with the shafts J² and J³ give the same a quarter-turn, so that the said shafts by their connection with the shafts J and J' turn the latter the same distance, whereby the rail-sections I, I', I², and I³ are given one- 10 quarter turn, so as to disconnect the rails A' and A² from the rail-sections A³ and A⁴ and connect the rails B' and B² with the rail-sections B³ and B⁴. A car now traveling on the track B passes over the continuous rails B' 15 and B², thus avoiding all jar when passing over the crossing.

The device for turning the shaft L is arranged as follows: On the left-hand end of the shaft L is secured a crank-arm L³, pivotally connected by a link L⁴ with the free end of a lever N, pivoted at N' near the middle of the track B, said lever N being provided with an offset part N² extending in an inclined position over the cable D, to be engaged by 20 a pulley D² held on the free end of a spring D³, secured on the cable-grip D' (see Fig. 5) of the car traveling on the track B in the direction of the arrow a'. When the pulley D² on the cable-grip engages the under side of this lever N, it raises the same, thereby pulling on the crank-arm L³, so as to turn the shaft L, whereby the shafts J, J', J², and J³ are turned, as above described, and the positions of the rail-sections I, I', I², and I³ are such as 25 to make the rails B' and B² continuous.

In front of the lever N is arranged a similar lever O, also adapted to be engaged by the pulley D² on the cable-grip, so as to raise the said lever O. The latter supports at its free 30 end a downwardly-extending rod O', supporting a pulley O², over which passes the cable D, so that when the lever O is raised by the grip of the car approaching the crossing said cable D is also raised to the position 35 shown in dotted lines in Fig. 2, whereby the said cable becomes disconnected from the grip and the latter swings sidewise, as previously stated, to remain disconnected from the cable until the crossing is passed. The 40 moment the pulley D² on the grip has left the end of the lever O the latter then drops to its original position, as shown in Fig. 2, so that the grip can pass over lever P to the left of the pulleys F' and F and over the cable C 45 without touching the latter.

In order to hold the cable C down while the grip passes over it, as described, a flat lever P is pivoted next to the lever O and carries on its free end a pin, on which is mounted a 50 pulley P', adapted to engage the top of the cable C when the lever P is swung downward by the grip passing over it and at the same

time over cable C. The lever P is held in an inclined normal position by a weighted arm P², as plainly shown in the drawings, and 55 serving to return the lever to its normal position after the grip has passed off the pulley end of the said lever.

On the right-hand side of the crossing, in the track B, is arranged a lever Q, similar in 70 construction to the levers N and O, previously described, and pivotally connected by a link Q' with an arm Q², secured on a shaft Q³, mounted to turn in suitable bearings and extending transversely on the track B below the 80 rails and under the cable D. The arm Q² carries a pulley Q⁴, engaging the under side of the cable D. An arm Q⁵, carrying a weight Q⁶, is also secured on the shaft Q³ and serves to hold the pulley Q⁴ in place against the under side of the cable D. When the grip of the car on track B, after having passed the crossing, engages the lever Q, it raises the latter, and by the link Q' swings the arm Q² upward, so that the pulley Q⁴ on the said arm 85 Q² raises the cable D to the position shown in dotted lines in Fig. 2. The upward swinging motion of the arm Q² is assisted by the weighted arm Q⁵, which swings downward as soon as it has passed its perpendicular position. The grip in passing from the bent part B⁸ to the straight part of the slot B' now 90 swings inward and again grasps the cable D, which will carry it and the car forward in the usual manner. The grip then engages a lever R, similarly constructed to the levers N and O, previously described, and pivotally connected by a link L⁶ with a crank-arm L⁵, secured on the shaft L. When the latter is turned by a car approaching the crossing in 95 the direction of the arrow a', then the said lever R is dropped into the position shown by dotted lines, and its weight on arm L⁵ prevents shaft L from turning, thus locking I, I', I², and I³. The lever R is also connected 100 with one end of a rope or chain R³, extending downward and passing under a pulley R², and then extending toward the crossing and 105 passing under a pulley R⁴, to which the end of the rope R³ is secured. The pulley R⁴ is 110 fastened on the shaft Q³, previously mentioned.

The operation is as follows: When a car traveling on the track B approaches the crossing, the grip of the car acts on the lever N 115 so as to turn the shaft L to change the position of the track-sections I, I', I², and I³, to make the rails B' and B² continuous, as previously described. As the grip advances the lever O is raised and by its rod O' and pulley O² raises the cable D, which, on account 120 of passing under the pulleys F, raises the latter, and also the frame G, supporting the other pulleys E and E', over which passes the cable C, so that the latter is also raised; but 125 the two cables are prevented from coming in contact with each other, as one passes under the pulleys F and F', respectively, and the other passes over the pulleys E and E', re-

spectively, both sets having their centers in one horizontal plane. When the grip nears the end of the lever O, it disengages the same by the grip swinging to the left on entering the curved part B⁸ of the slot B⁷, and thus permitting the cables C and D and their frame G to drop down to their former position. (Shown in Fig. 2.) The grip next comes in contact with the lever Q, so that the weight Q⁶ is thrown forward and downward, causing the raising of the cable D, &c., so as to allow the grip to swing in and grasp the cable D, which takes place when the grip leaves the curved part B⁸ and passes into the straight part of the slot B⁷. The grip next comes in contact with the lever R, so that the latter is raised, and by its rod L⁶ acting on the arm L⁵ turns the shaft L backward to its former position, whereby the several shafts J, J', J², and J³ are turned in the opposite direction, so as to move the rail-sections I, I', I², and I³ back into their normal position, whereby the rails A' and A² are made continuous. A car coming from the main track A finds the cables C and D in their proper position, and when a car on the cross-track B approaches the crossing the above-described operation is repeated, and thus the rail-sections I, I', I², and I³ are changed to make the rails B' and B² continuous.

It is understood that when the lever N stands in its natural inclined position the lever R stands horizontally, and vice versa, so that the car running in the direction of the arrow a' after crossing the track A finds the lever R in a lowermost inclined position, caused by the raising of the lever N. When the lever R swings downward, the rope R³ is slack and permits the counterbalancing weighted arm Q⁵ to swing downward, whereby the pulley Q⁴ and cable D are raised, as before described.

When the shaft L has been turned by the lever R to shift the track-sections I' I² I³, &c., the shaft will be locked in position until again turned by the lever N, as illustrated in Fig. 3.

Having thus fully described my invention, I claim as new and desire to secure by Letters Patent—

1. In a cable-railway crossing, the combination, with two cables crossing each other, of a frame adapted to be raised and lowered

and two sets of pulleys arranged thereon, one set of pulleys supporting one of the said cables, while the other passes under the other set of pulleys, substantially as shown and described. 55

2. In a cable-railway crossing, the combination, with two cables crossing each other, of a frame and two sets of pulleys arranged thereon, one set of pulleys supporting one of the said cables, while the other cable passes under the other set of pulleys, and a lever held in line with one of the said cables to be 60 engaged by the cable-grip and swung upward to raise the two cables and frame, substantially as shown and described. 65

3. In a cable-railway crossing, the combination, with two cables crossing each other, of a frame, two sets of pulleys arranged thereon, one set of pulleys supporting one of the said cables, while the other cable passes under the other set of pulleys, and a weighted lever adapted to be operated on by the cable- 70 grip and adapted to engage with its free end the said supported cable on its top, substantially as shown and described. 75

4. In a cable-railway crossing, the combination, with two cables crossing each other, of a frame, two sets of pulleys arranged thereon, one set of pulleys supporting one of the said cables, while the other cable passes under the other set of pulleys, a weighted lever adapted to be operated on by the cable- 80 grip, and a grooved pulley held on the free end of the said lever to engage the said supported cable, substantially as shown and described. 85

5. In a cable-railway crossing, the combination, with two cables crossing each other, of a frame and two sets of pulleys arranged thereon, one set of pulleys supporting one of the said cables, while the other cable passes under the other set of pulleys, a lever held in 90 line with one of the said cables to be engaged by the cable-grip and swung upward to raise the two cables and frame, and a pulley supported on the said lever and engaging the respective cable, substantially as shown and de- 95 scribed. 100
